Application filed August 13, 1892. Serial No. 443,032. Term of patent 7 years.

To all whom it may concern:

Be it known that I, ALBERT SCHOENHUT, a citizen of the United States, and a resident of Philadelphia, Pennsylvania, have invented a new and original Design for a Trumpet, of which the following is a specification.

o E is the tapered body of the trumpet, having at one end a mouthpiece F and at the other end a bell-mouth G. Attached to the body portion of the trumpet is an American flag D, which depends from the body of the trumpet.

I claim—

The design for a trumpet, as herein described, and as shown in the accompanying drawing.

In testimony whereof I have signed my name to this specification in the presence of two subscribing witnesses.

ALBERT SCHOENHUT.
